UNITED STATES PATENT OFFICE.

HENRY C. EGERTON, OF PASSAIC, NEW JERSEY, ASSIGNOR, BY MESNE ASSIGNMENTS,
TO WESTERN ELECTRIC COMPANY, INCORPORATED, A CORPORATION OF NEW YORK.

TELEPHONE APPARATUS.

1,188,053.

Specification of Letters Patent. Patented June 20, 1916.

Application filed April 20, 1914. Serial No. 833,228.

To all whom it may concern:

Be it known that I, HENRY C. EGERTON, a citizen of the United States, residing at Passaic, in the county of Passaic and State 5 of New Jersey, have invented a certain new and useful Improvement in Telephonic Apparatus, of which the following is a full, clear, concise, and exact description.

This invention relates to telephonic apparatus, and more particularly to telephone transmitters.

The object of this invention is to provide a new and improved transmitter of few and simple parts, which will be highly sensitive 15 to sound waves and capable of carrying a comparatively large current for a considerable period of time. The transmitter of this invention is microphonic in structure, that is, the sound-receiving diaphragm is 20 directly in contact with the resistance-varying material and constitutes one electrode of the device. The resistance-varying medium is contained within a metal cup and in sufficiently intimate contact therewith 25 that the heat generated in said granules will be readily conducted away by the metal. The support for the granule-containing cup is metal and so formed that it will when heated, bow in a direction to increase the 30 resistance to the flow of current through the granular material.

Other features of the invention relate to the details of the casing for rendering it moistureproof and other combinations of 35 parts and details of construction.

In the drawings—Figure 1 is a sectional view of a transmitter embodying this invention; and Fig. 2 is a detail perspective view of parts of the device before assembly.

As shown in the drawing, 5 is a transmitter mouthpiece of ordinary form secured to a front member 6 of a casing comprising the front member 6 and a back member 7. The back member is composed 40 of two members 8 and 9 separated and bent over at their margins to form an annular chamber within which the margin of the front member 6 is inserted. A rubber gasket 10 is inserted between the adjacent 45 faces of the front and back members 6 and 7 for the purpose of rendering the interior of the casing moistureproof.

Located within the casing in operative relation to the mouthpiece is a diaphragm

15, preferably of carbon, which is insulated 55 from the casing member 6 by means of insulating members 16 and 17. Located within the casing and in the rear of the diaphragm 15 is a supporting plate 18 having formed centrally thereof a cylindrical portion 19 for the purpose of receiving a granule-containing chamber, as will herein-after more fully appear. As will be noted, the supporting plate 18 is cupped, as shown at 20, adjacent the cylindrical portion 19, 60 and is provided with a plurality of openings 21, 21 to form a web of the cupped portion. This cupped portion 20 faces the diaphragm and is adapted to bow backwardly therefrom in response to a heating 65 of the granule container, thus separating the granular material and increasing the resistance through it.

Located within the cylindrical portion 19 is a granule-containing cup 25, the forward 75 margin of which is tapered or chamfered off away from the inner edges, as shown at 26. Located within said container and bearing against a shoulder 27 therein is an electrode 28. This electrode is secured in place by 80 means of a cupped spring 29 interposed between the electrode 28 and a closure 30, which is secured to the rear edge of the cylindrical member 19. The front edge of the cylindrical member 19 is recessed as shown 85 at 35 to receive a washer 36 of felt or other suitable material against which the front edge of the container 25 also bears. Located within the chamber formed between the front face of the electrode 28 and the rear 90 face of the diaphragm 15 is a quantity of granular material 37 which constitutes the resistance-varying medium of the device. The interior of this chamber has its wall covered with a thin layer of insulating 95 japan 38 which, although it forms sufficient insulation against the current through the granular carbon, permits the heat generated by the current to pass through. As shown, the felt ring or washer 36 is comparatively 100 thin so that a greater portion of the granular material 37 is in contact with the interior of the chamber than with felt ring so that the heat generated therein will be readily conducted through the walls of the 105 container 25 and the cylindrical portion 19 to the plate 18.

A spacer 40 is inserted between the front

face of the plate 18 and the rear face of the diaphragm 15, and is insulated from the plate 18 by means of an insulating washer 41. Terminal binding posts 45 and 46 are secured to the plate 18, the post 45 being insulated from said plate but in electrical contact with the spacer 40 and thus with the diaphragm 15, the post 46 being in electrical contact with the plate 18 only. These two posts comprise the terminals of the device.

What is claimed is:

1. In a telephone transmitter, a diaphragm, a resistance-varying medium in contact with said diaphragm, a container for said resistance-varying medium, and a thermostatic member carrying said con-

tainer and responsive to the heat generated therein.

2. In a telephone transmitter, a diaphragm, a resistance-varying medium in contact with said diaphragm, a container for said resistance-varying medium, and a supporting member carrying said container and responsive to the heat generated therein, said supporting member dished to bow away from the diaphragm when heated.

In witness whereof, I hereunto subscribe my name this 16 day of April A. D. 1914.

HENRY C. EGERTON.
